ABSTRACT

A torso structure for a simulated football player on a radio-controlled, motor-driven carriage. The torso structure has pivoted arms. The torso is rotated by a motor and the arms are geared to a common non-rotating pinion gear so that the arms rotate in opposite directions responsive to the rotation of the torso.

FIG. 1.

FIG. 2.

TORSO STRUCTURE FOR A MECHANICAL PASS RECEIVER

This invention relates to football practice devices for improving the accuracy of a football thrower or passer, and more particularly to an improved torso structure for a simulated football pass receiver of the type disclosed in my co-pending application, Ser. No. 838,102, filed July 1, 1969, (now U.S. Pat. No. 3,573,867) and entitled "Mechanical Pass Receiver".

A main object of the present invention is to provide an improved torso structure for a simulated football player mounted on a radio-controlled, motor-driven carriage, wherein the movement of the torso portion of the simulated football player's body is controlled by steering action of the carriage and wherein the arms of the simulated torso rotate in opposite directions responsive to the rotation of the torso, the improved structure involving only a few parts, being easy to install, being reliable in operation, and being inexpensive to fabricate.

A further object of the invention is to provide an improved torso structure for a simulated football player of the type disclosed in my above-identified co-pending application, Ser. No. 838,102, the improved structure of the present invention involving a minimum amount of gearing, being arranged so that the parts thereof move smoothly without binding, and being further arranged so that the torso and the arms pivoted thereto can move smoothly and in a lifelike manner.

Further objects and advantages of the invention will become apparent from the following description and claims, and from the accompanying drawings, wherein:

FIG. 1 is a top plan view of the improved torso structure of the present invention with the body covering omitted.

FIG. 2 is a vertical cross-sectional view taken substantially on the line 2-2 of FIG. 1.

A prime purpose of the present invention is to provide a simplified torso structure for a simulated football player of the type mounted on a radio-controlled, motor-driven carriage, such as is disclosed in my co-pending application Ser. No. 838,102, above-identified. As is described in said co-pending application, the simulated body is mounted on a carriage having a driving motor and being steerable in accordance with radio signals received thereby, and the simulated football player has a body consisting of a fixed lower portion secured to the associated carriage, and having the hollow top portion 40 to which is swivelly connected the simulated torso 37. The lower portion of the simulated football player includes the legs fixedly secured to the frame of the associated carriage, the legs merging in said hollow top portion 40, representing the simulated player's hips. Said top portion 40 is provided with a horizontal top wall 41 and the hollow simulated torso 37 is vertically swiveled to the lower body portion by being rotatably journaled to an upstanding vertical shaft 42 fixedly secured centrally in the top wall 41 and projecting upwardly into the hollow torso portion 37.

In the improved torso structure of the present invention, the shaft 42 extends through an aperture provided in the bottom wall 109 of the torso 37 and an upstanding ball-bearing assembly 200 is provided to form the swivel connection, the outer race of the assembly 200 being rigidly secured to bottom wall 109 and the inner race portion being engaged around the shaft 42. Rigidly

secured to the bottom of wall 109, concentrically with shaft 42, is a gear 201, and meshing with the relatively large gear 201 is a pinion gear 202 connected to the output shaft of the torso-swivelling motor 108, which is secured in the portion 40 of the body beneath the top wall 41 thereof.

The torso covering is shown in dotted view in FIG. 2, whereas the framework of the torso is shown in full line view. Thus, the torso framework comprises a pair of vertical discs defining plate elements transversely arranged adjacent the shoulder portions of the simulated torso, designated at 204, 205.

The discs 204, 205 are rigidly connected to the generally oval bottom wall 109 by a pair of upwardly and outwardly inclined strut bars 206, 207, said bars being provided at their lower end portions with opposite pairs of triangular gusset plates 208, 208. The arm discs 204, 205 are further rigidly connected by a cross-bar means comprising a pair of angle bars 209, 210 rigidly secured to and extending horizontally inwardly from the lower portions of the discs 204, 205 and connected at their inner ends by a downwardly offset center angle bar 211. The angle bars 209, 210 are provided at their inner ends with transverse filler plates 212, 213 and the ends of the top flange 214 of the center angle bar 211 are rigidly connected, as by welding, to the bottom edges of the filler plates 212, 213. Mounted on the inner end portions of the top flanges 215, 216 of angle bars 209, 210 are respective upstanding bearing blocks 217, 218, and respective arm-supporting shafts 219 and 220 are rotatably supported centrally in the discs 204, 205 and in the bearing blocks 217, 218, said shafts having respective opposing differential bevel gears 219', 220' secured to their inner ends, as is clearly shown in FIG. 2. Rigidly secured to the outer ends of the shafts 219, 220 are respective arm-supporting discs 221, 222 to which are rigidly secured the respective simulated player's arms 223, 224.

The central angle bar 211 is provided with an aperture in the center portion of its top flange 214 through which extends a shaft element 225, shaft element 225 being journaled in a vertical sleeve 226 rigidly secured to flange 214 and provided at its upper portion with an interior bearing bushing 228. Secured to the top end of the shaft 225 is a pinion gear 229 which meshes with the opposing bevel gears 219', 220', defining therewith a differential gear assembly. The lower end of shaft 229 is connected by a universal joint assembly 230 to the top end of the upstanding shaft element 42.

As will be readily apparent, when the motor 108 is energized to cause the simulated torso 37 to swivel around the axis of the shaft 42, the bevel gears 219' and 220' are forced to rotate in opposite directions, since they mesh with the substantially fixed pinion gear 229, whereby the simulated arms 223, 224 are caused to rotate in opposite directions, to provide the appropriate positioning of a pivoted basket ring connected to the arms in the manner described in the above-identified pending application Ser. No. 838,102.

The provision of universal joint 230 allows sufficient freedom of movement of the upper shaft element 225 with respect to the lower shaft element 42 to prevent binding of the parts during the swiveling action of the simulated torso 37, and allows for a reasonable degree of flexure of the torso framework during the operation of the simulated pass receiving apparatus.

The operation of the simulated pass receiver is fully described in the above-identified co-pending application, and the improved torso structure of the present invention does not in any way change the general operation of the device.

While the specific embodiment of an improvement in torso structure for a practice football pass receiver has been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. In a practice football pass receiver, a simulated body lower portion, upstanding shaft means non-rotatably secured to said body lower portion, a simulated torso swiveled on said lower portion for rotation around said upstanding shaft means, said simulated torso having simulated arms pivoted to opposite sides thereof, and differential gear means coupling said arms to said upstanding shaft means, whereby rotation of said simulated torso with respect to said body lower portion causes rotation of said simulated arms in opposite directions, wherein said simulated torso includes a frame comprising a bottom wall, upwardly and outwardly inclined strut bars secured to said bottom wall, transverse vertical plate elements secured to the top ends of said strut bars, and cross-bar means connecting said transverse vertical plate elements, said simulated arms being pivoted in said vertical plate elements and

said upstanding shaft means extending rotatably through the mid-portion of said cross-bar means.

2. The practice football pass receiver of claim 1, and a drive motor mounted on said simulated body lower portion and gear means coupling said drive motor to said simulated torso.

3. The practice football pass receiver of claim 2, and wherein said last-named gear means comprises a drive gear on said motor and a driven gear secured to said bottom wall concentrically with said upstanding shaft means and meshing with said drive gear.

4. The practice football pass receiver of claim 1, and wherein said mid-portion is downwardly offset relative to the end portions of said cross-bar means and is provided with an upstanding bearing sleeve surrounding said upstanding shaft means.

5. The practice football pass receiver of claim 4, and wherein said simulated arms are provided with respective inwardly extending horizontal shafts, and wherein said differential gear means comprises a pinion gear secured on the top end of said upstanding shaft means and respective bevel gears secured on the inner ends of said horizontal shafts meshing with said pinion gear, said upstanding bearing sleeve being received between said bevel gears.

6. The practice football pass receiver of claim 5, and wherein said upstanding shaft means includes a universal joint located subjacent said downwardly offset mid-portion of said cross-bar means.
